UNITED STATES PATENT OFFICE.

PHILIP H. HOLMES, OF GARDINER, MAINE.

MACHINE FOR MAKING WOOD FIBER.

SPECIFICATION forming part of Letters Patent No. 291,848, dated January 8, 1884.

Application filed November 26, 1883. (No model.)

To all whom it may concern:

Be it known that I, PHILIP H. HOLMES, of Gardiner, in the county of Kennebec and State of Maine, have invented certain new and useful Improvements in Machines for Making Wood Fiber; and I do hereby declare the following to be a full, clear, and exact description of the invention, such as will enable others skilled in the art to which it appertains to make and use the same.

My invention relates to an improvement in machines for making wood fiber. Letters Patent No. 228,899 were granted to me June 15, 1880, for an improvement in wood fiber as 15 a new article of manufacture, and for the process of and machine for producing the improved article.

My present invention relates more especially to an improvement on the machine covered by 20 the patent referred to, the object being to provide a machine of such construction and arrangement of parts that a block or piece of wood may be quickly converted into dry wood fiber practically uniform in length and size 25 and by a minimum expenditure of power. A further object is to produce a machine of this character having an attachment for retaining a straight and sharp edge on the cutters for quite a length of time, and thus obviate the 30 necessity for continually sharpening the knives or cutters.

With these ends in view, my invention consists, first, in a machine for producing wood fiber for paper-pulp or other purposes, the 35 combination, with suitable devices for supporting and rotating a block or pieces of wood, of a knife or cutter arranged to be reciprocated and sever the fiber from the block by a drawing cut.

My invention further consists in the combination, with suitable devices for supporting and rotating a block or pieces of wood, of a series of knives or cutters, made from a single piece of material, or made separately and 45 secured together, and devices for reciprocating said knives or cutters and severing the fiber by a drawing cut.

My invention further consists in the combination, with devices for supporting and rotating 50 a block or piece of wood, of a cutting-blade provided with grooves for subdividing it into a series of knives or cutters.

My invention further consists in the combination, with suitable devices for supporting and rotating a block or piece of wood, of a 55 knife or cutter for severing the fiber from the block, and means for sharpening the knife while the machine is in operation.

My invention further consists in the combination, with suitable devices for supporting 60 and rotating a block or piece of wood, of a series of knives or cutters for severing the fiber from the block, and means for sharpening the knives or cutters while the machine is in operation.

My invention further consists in the combination, with suitable devices for supporting 65 and rotating a piece of wood, of a series of reciprocating knives or cutters arranged and adapted to sever the fiber by a drawing cut, 70 and means for sharpening said cutters while the machine is in operation.

My invention further consists in certain other features of construction and combinations of parts, as will be hereinafter described, 75 and pointed out in the claims.

In the accompanying drawings, Figure 1 is a plan view of a machine embodying my invention. Figs. 2 and 3 are views in side elevation. Figs. 4 and 5 are end elevations. 80 Fig. 6 is a sectional view through bed, showing feed-works. Fig. 7 is a detached view of the sharpener. Fig. 8 is a detached view of the forked nuts. Fig. 9 is a view of the slab-holder, and Fig. 10 is a view in cross-section 85 of the same.

A represents the main frame of the machine.

B is the head-stock, in which is journaled the live-spindle *a*, having secured thereto the driving-pulley *a'*, and provided at one end with 90 the chuck *a''*.

C is the tail-stock, provided with the adjustable mandrel *b*. Instead of employing the mandrel *b*, I use a live-spindle, similar to spindle *a* in larger machines, and provide means 95 for imparting endwise adjustment to said spindle, for securing and removing the block of wood D, which latter, in the present instance, is secured between the mandrel and chucks, and is rotated at any desired speed by the live-spindle.

To one end of the live-spindle *a*, which also constitutes the main or driving shaft of the machine, is keyed a pinion, *c*, which meshes

with the gear-wheel c' , journaled on a stud, c^2 , secured to an adjustable lever, c^3 , the latter being provided with an arc-shaped slot, c^4 , through which extends a bolt, c^5 . By means 5 of the nut c^6 the lever and gear may be secured in any desired adjustment. Gear-wheel c' meshes into a larger gear-wheel, c^7 , journaled on a shaft, c^8 . Upon the projecting end of the shaft c^8 is journaled one end of a link, D, the 10 opposite end of which supports the outer end of a shaft, D', while the inner end of the latter is supported in the lower end of a link, D'', the upper end of which is journaled on a shaft, D³, mounted in the traveling rest D⁴. Gear-wheel c^7 meshes into a gear-wheel, d, journaled on the shaft D', while the gear d meshes 15 into a gear, d', mounted on the shaft D³. The system of gearing above described is regulated as to speed by means of different-sized gears 20 placed on the lever, stud, or bearing c^2 , said lever enabling the position of the gear to be regulated, so as to transmit motion from the pinion c to the large gear-wheel c' . The link-connections described enable the gears 25 transmit motion to the shaft D, mounted in the traveling rest D⁴.

To the under side of the traveling rest are secured or cast integral therewith the depending blocks E E', which are screw-threaded, 30 and constitute traveling nuts. Shaft E² is supported in bearings e^2 e, and is provided with a screw-threaded portion, e^3 , that engages in the traveling nut E, while the forward end of the shaft is furnished with a hand-wheel, E⁵, for 35 adjusting the position of the traveling rest by hand. Shaft E³ is supported in bearings e^3 e⁴, and has keyed to one end thereof a bevel-pinion, e^5 , which meshes with a bevel-pinion, e^6 , keyed to a counter-shaft, e⁷, supported in bearings 40 e^8 e⁹. Near the opposite end of the counter-shaft e⁷ is keyed a bevel-pinion, e^{10} , which meshes with a bevel, e^{11} , keyed to the shaft E². On the shaft c^8 , which is driven by the gear-wheel c' , is keyed a pinion, F, which meshes 45 with a gear-wheel journaled in the outer end of a shaft, F², supported in an adjustable apron, F³, the latter being mounted on the shaft c^8 . To the opposite end of the shaft F² is secured 50 a worm, F⁴, that is adapted to engage a worm-gear, F⁵, keyed to the shaft E³. A lever, G, is connected by a link, G', to the adjustable apron F³, and is raised and lowered by means of the hand-lever G², which latter has pivoted thereto a handle, G³, that is connected by a 55 rod, G⁴, with a spring-actuated catch, G⁵. When the lever G² is raised so as to throw the worm in engagement with the worm-gear, the catch G⁵ engages with the cross-piece g and retains the parts in gear. By raising the handle G³ the catch is disengaged, thereby allowing 60 the apron to be lowered, and thus disengage the worm from the worm-gear. When the worm is in gear with the worm-gear, rotary motion is transmitted from the shaft c^8 to 65 both of the screw-shafts E² E³, and thus the traveling rest is fed forwardly to its work in an even and uniform manner, owing to the

fact that power is applied thereto at its opposite ends. By disconnecting the worm and worm-gear the traveling rest is run back by 70 hand; or, if desired, a clutch might be provided for running it back by power.

The traveling rest D⁴ is constructed with grooved guideway H, in which slides the rear edge of the reciprocating head H'. Wearing- 75 plates h h' are inserted in the guideway H, so as to engage the rear edge and top of the rear portion of the head. These parts are adjusted by means of the set-screws h², to compensate for wear. The forward portion of the head 80 is grooved, as at h³, and engages guides h⁴, so as to retain it in position and insure an accurate adjustment of the parts. As there are many different ways for connecting the reciprocating head to the traveling rest, I do not 85 limit myself to the construction and arrangement of parts shown and described.

To the traveling head is secured a forked nut, I, which engages the double screw I', the latter being a continuation of the shaft 90 D³. By rotating the shaft D³ the head H' is reciprocated in opposite directions.

To the head H, at one side thereof, is secured the trip W, which may be adjusted to automatically trip the spring-actuated catch 95 and disengage the worm from the worm-gear and stop the feed of the knives to the work.

J is the knife-blade, which may be made of a single piece of steel, but is preferably constructed of an iron bar having a steel facing 100 welded thereto. Blade J is beveled on its under side to form a sharp cutting-edge, j. The upper face of the blade is provided with narrow grooves j', which are planed any desired depth, and serve to subdivide the blade into a 105 series of knives, j², the width of which determines the length of the fiber produced as each knife operates to sever the fiber from the block and produce fiber of a very fine and even quality and of a length equal to the 110 width of the knife; hence, by varying the width of the knives, fiber of any desired length may be produced. As fiber of different lengths may be desired for different purposes, each machine may be provided with a set of knives 115 of different widths, so that by simply exchanging knife-blades any desired length of fiber may be produced. Knives constructed in the manner described possess many important advantages over a gang of separate 120 and independent knives or cutters. In the first place, my improved knives are cheaper in first cost, as a single plate is quickly converted into a series of knives by simply grooving the upper face of the blade in the manner 125 described; secondly, the knives are retained in accurate adjustment by bolts or screws K passing through the elongated slot K' in the blade, and hence by adjusting the blade the entire series of knives are quickly and accurately adjusted and firmly retained against displacement; thirdly, by forming the knives 130 integral from a single blade the cutting-edges of the series may be readily sharpened, and

be kept perfectly straight, and thereby insure uniform work in the operation of the machine. The knives are fed forward against the revolving block of wood at any desired rate of speed by means of changeable gears on the stud c^2 , and thus produce fiber of any required size. For some purposes a finer and more delicate fiber is required than for others—as, for instance, in the manufacture of very thin paper a fine and delicate fiber is required for the pulp, and hence in such case a slow feed is called for, while on the contrary a faster feed is resorted to in the production of a coarser grade of fiber, which is adapted to be manufactured into coarser stock for paper or other purposes. The knives are continually fed forward to the work, and are at the same time reciprocated, so as to produce a drawing cut, which is one of the important features of my improvement, as less power is required to operate the machine and convert a block of wood into dry fiber by knives producing a drawing cut than by stationary knives. Again, the knives operating in the manner described will retain their cutting-edge much longer than knives held stationary to their work.

While I have shown and described a double screw and forked nut for reciprocating the head with the knives connected therewith, I in nowise restrict myself to such devices for accomplishing this result, as I may use a rack and gear or a slide operated by an eccentric or crank or any other arrangement for reciprocating the knives, and hence consider myself entitled to the employment of any suitable devices for the purpose stated.

I will now proceed to describe the mechanism for sharpening the knives.

To the shaft D^3 is keyed a gear-wheel, L , which meshes with a gear-wheel on the counter-shaft L^2 . Eccentrics $M M'$ are secured to the counter-shaft L^2 . The arms $l l'$ of the eccentric-straps l^2 are journaled upon bearing-pins l^3 , attached to the slides $N N'$. Each slide is mounted in a guide, N^2 , which is pivoted at n , while a set-screw, N^3 , engages its outer end, and hence by means of the set-screw the guide may be adjusted to any desired angle. Upon the upper surface of each slide is secured a water-stone, O , the lower edges of which rest against a ledge, o , on the slide, while its upper edge is secured by a block, o' , and a set-screw, o^2 . These knife-sharpener are located on opposite ends of the revolving block, and are reciprocated at right angles to the movement of the knives; and, further, are arranged so that each sharpener will operate on a little more than one-half of the length of the blade of the entire series of knives. Hence it will be observed that while the machine is in operation and the knives are severing the fiber from the rotating block of wood, the sharpeners are also in operation and engage the beveled edges of the knives and retain an even and sharp cutting-edge on the entire series, thus enabling the machine to be operated

for a comparatively great length of time without necessitating the removal of the knives for grinding; and, again, insuring a uniform grade of fiber as to size as well as length. The water-stones are supplied with water through pipes communicating with a tank or other source of supply. (Not shown.)

While I have shown and described reciprocating sharpeners as adapted for the purpose set forth, I do not limit myself to such construction and arrangement of sharpeners, as I may use rotary sharpeners consisting of rotary stones or emery-wheels with or without beveled faces, and mounted so as to admit of adjustment to adapt themselves to the adjustment of the knives; or, instead of rotary sharpeners, I may use endless belts of emery supported on rollers mounted in an adjustable frame, and arranged to engage and sharpen the knives. The combination of a knife-sharpener with the knives, whereby the latter may be sharpened while the machine is in operation is an important feature of my invention, because it is essential to the best results that the knives shall have their cutting-edges retained very sharp and in alignment with each other. If it were necessary to remove the knives to resharpen them whenever they had become too dull for use, much valuable time and labor would be expended in such work, and under such conditions it would be impossible to obtain a uniform grade and quality of fiber; but by the employment of sharpeners that produce a drawing movement across the edges of the knives while the latter are in operation their cutting-edges are retained perfectly true and very sharp for a great length of time, thus materially increasing the producing capacity of the machine as well as insuring a uniform grade of fiber. As the work imposed upon the knives gradually lessens as the block is cut away and its diameter decreased in size, I may employ variable speeds for driving the live-spindle and run it at a slow speed while the block is first operated upon, and when partly reduced run it at a higher rate of speed throughout the remainder of the operation.

Instead of operating on blocks of wood, I may convert slabs into fiber by the following method: In Fig. 9, QQ' represent arbors, which are respectively secured to the spindle and mandrel of the machine. Each arbor is provided with the inwardly-projecting flanges q^2 , which serve as rests for the slabs, while the ends of the arbor are provided with projections q^2 , which penetrate the ends of the slabs and retain them against displacement. The slabs are sawed into the form as shown in Fig. 9, and are then secured at their opposite ends to the arbors, the adjacent edges of the slab making joints, as shown. The arbors, with the slabs fastened thereto, are then placed in the machine, which will convert the greater portion of the slab into fiber, and thus enable me to utilize a comparatively worthless product of saw-mills. R represents a trough, into which the fiber is thrown as it leaves the block, and by means of

which the fiber is conveyed from the machine. This trough may be provided with an endless belt, to serve as a conveyer; or the trough may be closed and serve as a trunk, and an exhaust fan connected therewith for removing the fiber by suction or blast, as may be preferred. While I prefer to employ a series of knives for forming the fiber, as they not only sever the fiber from the block, but also cut it in the desired lengths, 5 I may use a simple knife or blade for severing the fiber, and employ separate knives or cutters, either stationary or revolving, for cutting grooves in the block before operated upon by the severing-knife. Again, the knives, instead 10 of being made integral, as described, may be made separate and independent, and secured to or within a holder by clamping screws or bolts.

As it is evident that changes may be made 20 in the construction and arrangement of the mechanism and gearing for feeding the knives, also for reciprocating the knives, also for actuating the sharpeners, and also in the construction of the knives and sharpeners, without involving a departure from my invention, I would 25 have it understood that I do not restrict myself to the particular construction and arrangement of parts shown and described.

It is unnecessary for me to herein set forth 30 characteristics that distinguish dry-wood fiber from the ordinary and well-known wet-wood pulp, nor the advantages attending the use of dry fiber, as such matters, together with the prior art, have been clearly set forth in my 35 patent heretofore referred to.

Having fully described my invention, what I claim as new, and desire to secure by Letters Patent, is—

1. In a machine for making wood fiber, the 40 combination, with devices for supporting and rotating a block or pieces of wood, of a knife arranged to be moved and sever the fiber by a drawing cut, substantially as set forth.

2. In a machine for making wood fiber, the 45 combination, with devices for supporting and rotating a block or pieces of wood, of a series of knives and suitable devices for reciprocating said knives and severing the fiber by a drawing cut, substantially as set forth.

3. In a machine for making wood fiber, the 50 combination, with devices for supporting and rotating a block or pieces of wood, of a series of knives and devices for feeding the knives to their work and for reciprocating them and

severing the fiber by a drawing cut, substantially as set forth. 55

4. In a machine for making wood fiber, the combination, with devices for supporting and rotating a block or pieces of wood, of a blade provided with grooves that subdivide the blade 60 into a series of knives, substantially as set forth.

5. In a machine for making wood fiber, the combination, with devices for holding a block of wood, of a series of knives adapted to convert the wood into fiber, and means for sharpening the knives while the machine is in operation, substantially as set forth. 65

6. In a machine for making wood fiber, the combination, with devices for supporting and 70 rotating a block or pieces of wood, of a series of knives, devices to feed and reciprocate said knives, and means for sharpening the knives while the machine is in operation, substantially as set forth. 75

7. In a machine for making wood fiber, the combination, with devices for rotating a block or pieces of wood, of reciprocating knives, a reciprocating knife-sharpener, and means for adjusting the angle of inclination of said sharpener, substantially as set forth. 80

8. In a machine for making wood fiber, the combination, with devices for rotating a block or pieces of wood, of reciprocating knives, a reciprocating slide having a knife-sharpener 85 removably secured thereto, and means for varying the angle of inclination of said slide, substantially as set forth.

9. In a machine for making wood fiber, the combination, with devices for rotating a block 90 or pieces of wood, of reciprocating knives and reciprocating knife-sharpener, located at opposite sides of the transverse center of said knives, substantially as set forth.

10. In a machine for making wood fiber, the 95 combination, with devices for rotating a block or pieces of wood, of reciprocating knives for severing the fiber by a drawing cut and a trough for conveying away said fibers, substantially as set forth. 100

In testimony whereof I have signed this specification in the presence of two subscribing witnesses.

PHILIP H. HOLMES.
